Inventor:
Henry Baetz

By Harry A. Beimer
Attorney

UNITED STATES PATENT OFFICE.

HENRY BAETZ, OF ST. LOUIS, MISSOURI.

AIR HEATER.

Application filed May 1, 1923, Serial No. 635,912. Renewed October 22, 1924.

To all whom it may concern:

Be it known that I, HENRY BAETZ, a citizen of the United States, residing at St. Louis, State of Missouri, have invented certain new and useful Improvements in Air Heaters, of which the following is a specification.

My invention has relation to improvements in air heaters and the method of mounting them, and consists in the novel features of construction more fully set forth in the specification and pointed out in the claims.

The object of the invention is to provide an air heater for foundries or rolling mills or other buildings wherein the entire floor space is utilized and cannot accommodate the heating apparatus. In heating buildings of this kind I provide an air heater that may be mounted upon the pillars supporting the crane rails or the roof. In order to have the hot air discharged from the heater in planes that will permit it to be immediately available to the workmen, I invert the heater, that is, arrange it so that the cold air will be taken into the heater at the top, and the heated air will be discharged at the bottom. I find this desirable since it enables the heaters to be mounted a considerable distance above the floor. Further objects are to provide an air heater in which the air intake may be adjusted to different heights from the floor, and to provide movable baffles in the air discharge pipe so that the heated air may be directed up or down as desired. Further advantages will be apparent from a detailed description of the invention in connection with the accompanying drawings, in which—

Figure 1 is more or less an outline view of a building to be heated with my improved heater mounted on a pillar some distance above the floor; Fig. 2 is a side elevation of my improved air heater with parts broken away to more clearly show the invention; Fig. 3 is a side elevation looking at an angle of 90° from Fig. 2, parts being broken away; Fig. 4 is an enlarged view of the end of one of the hot air outlet pipes showing the arrangement for moving the baffles in said pipe; Fig. 5 is a cross-sectional view taken on the line 5—5 of Fig. 4.

Referring to the drawings, B represents the building to be heated wherein there is a

crane C adapted to travel on the track T supported by pillars P, P, etc. The building is heated by my improved air heater H mounted on a pillar P, it being understood that there are as many heaters H as is necessary to properly heat the building. The heater H is supported on pillar P by means of brackets 1, 1; and is provided with air intake openings O in opposite sides of the heater casing 2. The opening O on the side of the casing adjacent the pillar P communicates with a vertically disposed air intake pipe 3, while the opening O on the opposite side of the casing communicates with the top section 4 of a series of telescopic pipe sections 4, 5, and 6, the object of which is to enable these sections to be collapsed for the purpose of enlarging the floor space about the heater when this is necessary. At the same time the sections 5 and 6 may be telescoped within section 4 for the purpose of furnishing the opening O with warmer air when it is desired. Within the casing 2 between the openings O, O a multi-vaned fan 7 is mounted on a shaft 8 supported in bearings 9, 9 within the pipes 3 and 4, the shaft 9 also carrying a pulley 10 at one end, over which is passed a belt 11, said belt also passing over pulley 12 of a small motor 13 resting on a platform 14 secured to casing 2.

Within the casing 2 and below the multi-vaned fan 7 is a bank of steam coils 15 having an inlet 16 and an outlet 17. The casing 2 terminates at its lower end in a pair of rectangular discharge pipes 18, each of which is provided with a plurality of dampers 19, 19, just inside the outlet, said dampers being pivotally mounted, and those in each pipe being connected by a link 20 which enables the dampers to be adjusted in unison, so that the hot air discharging from the pipes 18 may be projected up or down as desired. The dampers 19, 19 are held in their adjusted position by means of a pin 21 passing through one end of link 20 and the lever arm 22 of one of the dampers 19, said pin being insertable in any one of a series of holes 23 in a quadrant 24 secured to the side of each pipe 18. The outer reduced portion 21' of pin 21 has a spring 25 coiled about it, said spring maintaining the pin in the quadrant hole 23 to hold the dampers against movement.

In the operation of my heater the cold air

is drawn into the casing 2 through pipe 3 and telescopic pipes 4, 5, and 6 by the fan 7 and is then forced downwardly through the casing over the bank of steam coils 15 and 6 out through the pipes 18.

Having described my invention, I claim:

1. In an air heater having an air intake opening at the top and an air discharge opening at the bottom, a telescopic intake 10 pipe connected with the intake opening, an outlet pipe connected with the outlet opening, a heating element between the intake and the outlet openings, said outlet pipe having a plurality of air deflectors, said deflectors being connected on the outside of the pipe, and means for locking said deflectors 15

in any desired position within suitable limits.

2. In an air heater having an air intake opening at the top and an air discharge 20 opening at the bottom, an outlet pipe connected to the outlet opening, a heating element between the intake and outlet openings, said outlet pipe having a plurality of 25 air deflectors, said deflectors being connected on the outside of the pipe, and means for locking said deflectors in any desired position within suitable limits.

In testimony whereof I hereunto affix my signature.

HENRY BAETZ.
